UNITED STATES PATENT OFFICE.

CHAUNCEY N. DUTTON, OF CAMDEN, NEW JERSEY, ASSIGNOR TO THE FUEL GAS AND ELECTRIC ENGINEERING COMPANY, (LIMITED,) OF PITTSBURG, PENNSYLVANIA.

OSCILLATING METER.

SPECIFICATION forming part of Letters Patent No. 394,561, dated December 18, 1888.

Application filed November 4, 1885. Serial No. 181,864. (No model.)

To all whom it may concern:

Be it known that I, CHAUNCEY N. DUTTON, of Camden, in the county of Camden and State of New Jersey, have invented certain new and 5 useful Improvements in Meters, of which the following is a specification, reference being had to the accompanying drawings.

My invention consists in certain improvements in fluid-meters, constituting a duplex 10 oscillating meter, of which the following is a description, reference being made to the accompanying drawings.

In the drawings, Figure 1 is a longitudinal section substantially central. Fig. 2 is a transverse section. Fig. 3 is a reverse transverse section. Fig. 4 is a plan. Fig. 5 is a longitudinal section, and Fig. 6 is a transverse section.

Referring to the parts by letter, A is a meter-case, formed in two halves or parts and united on a substantially horizontal line.

B is the functional part, and C is a cover.

In order to securely unite the two parts of the case I form lugs D D, symmetrically disposed in pairs, on the upper and lower halves, and provide bolts E E, bearing in the lugs and securing the parts together, the joint being properly packed.

F F are partitions dividing the functional part B into chambers, G being a central chamber, H H measuring-chambers, and I I expansion-chambers, which connect one with the other, forming practically one chamber.

K K are inwardly-projecting portions of the case A, forming displacers and reducing the cubical capacity of the measuring-chambers H H.

When the case has the displacers K K, formed as above described, it is necessary to 40 dry-core the entire interior of the part B. In order to mold the said part in green sand, I may cast the shell without the inwardly-projecting portions, and subsequently form the displacers K K of a suitable cement or other 45 plastic substance, compressing it within molds to obtain the right contour. Such a construction is shown in Fig. 5.

L is a fluid filling the measuring-chambers H H, and more or less filling the expansion-

chambers I I. This fluid must be of different 50 specific gravity from and practically insoluble in the fluid to be measured.

M M' M' are oscillating measuring-cups which dip into the fluid L and the measuring-chambers H H and work therein. They are 55 closed on all sides save that which dips into the fluid L.

N N N' N' are yokes connecting the cups M M and M' M', respectively, each pair of 60 cups being connected and supported independently.

O O' are arms or extensions formed on the inner yokes, N and N', respectively, the function of which will be hereinafter set forth.

n n are lugs formed on the yokes N N', and 65 n² n² pointed bearing-screws on which the cups rock.

P P are lugs formed on the case, and Q a central pillar.

R R are abutment-screws working in the 70 lugs P, and r r are bearings formed therein and in pillar Q for the points of the bearing-screws n² n². This construction is shown only in Figs. 1, 2, 3, and 4. A different construction is shown in Figs. 5 and 6, when the central pillar, Q, the lugs n n, the bearing-screws n² n², and bearings r r are omitted. In the latter construction a³ is a round rod extending transversely across the meter; b³, screws working 75 in the case-lugs P P; c³, open bearings formed 80 in the heads thereof for receiving and supporting the ends of the rod a³, and d³ pins securing it therein.

e³ are central bosses on the yokes N N N' N', and f³ holes through which the rod a³ passes, 85 thus providing bearings on the rod for both sets of cups.

h³ h³ are collars slipped on the rod, and i³ i³ set-screws for securing them in position, thus confining the cups in proper planes.

S S' S' are tubes formed in the case and open at one end into the measuring-cups M M', respectively; at the other (through valve-ports) directly into the chamber G, except when covered by the valves.

T is the inlet-pipe, (or outlet, as may be.) It opens into a chamber, T', and thence through the central ports in the valve-seat into the

valves centrally between the orifices of the tubes S S and S' S'.

A² is the outlet (or may be inlet) pipe.

U U' are slide-valves of ordinary construction.

V is the valve-seat, and W W guides. The valve-seat is inclined transversely at an angle of about forty-five degrees, and the orifices of the ports and tubes are so disposed that no fluid suspended in the gas can trap the meter. The inclination of the valve-seat secures a drainage at its lower angle of inclination, which would be wanting in a valve-seat of other construction, while the weight of the valve, which would otherwise require a spring or other mechanical appliance to preserve its contact with the valve-seat, is sufficient to hold it in place. A free drainage at the valve-opening, and also along the tubes, is necessary to prevent the accumulation of a fluid before the flow of gas which would obstruct or prevent its passage. In order to prevent this in any degree, I make the outer ends, X, of the ports and the adjacent faces of the tubes S S and the chamber T' horizontal, or dipping slightly toward the exit.

In order to control the valves U U', I provide a crank-shaft, a, having bearings and support in a chair, b, which is secured to the meter-case.

c c' are crank-disks suitably secured on the ends of the crank-shaft a.

d is a crank-pin on the disk c', and e a link connecting it with the valve U'.

f is the link-pin on the valve. g is a double or set-off crank-pin on the disk c, and is provided with two bearings, the inner one, serving for a link, h, connecting it with the valve U by means of the link-pin i. This bearing has a quarter-lead on the crank-pin d. The outer bearing of the crank-pin g serves as a bearing for two links, k and l, and has an angular lead on the inner bearing equal to the mean divergence of the links e and h from the horizontal. The links k and l connect the set-off portion of the crank-pin g with the arms O and O', respectively, by means of the link-pins m and m'. The pin m on the arm O of the yoke N is to one side of the screws n² and the axis of the bearing-points and perpendicular to the vertical screws n². The pin m' on the arm O' of the yoke N' is in the vertical axis of the yokes N' N' and as much below the axis of the bearing-points as the center of pin m is to one side thereof. This construction gives the cups M M and M' M' and the corresponding valves a quarter-lead one on the other.

It will be observed that in Figs. 1, 2, and 3 the functional part of the meter is its lower half, and that the cups rest on their bearings, while in Figs. 5 and 6 the upper part is the functional part, and the cups are suspended from their bearings.

The difference between the two forms shown is this: That shown in Figs. 1 to 3, inclusive, is provided with a sealing-fluid, L (necessarily

a liquid,) of specific gravity greater than that of the fluid to be measured, while the second form is provided with a sealing-fluid (either liquid or gas) of specific gravity less than that of the fluid to be measured. The first form is adapted (by using a proper sealing-liquid) to measure any known fluid except mercury, while the second form is of more limited application, being adapted to measuring liquids only, and especially designed as a water-meter, with the intention of using air as a sealing-fluid.

The fluid can pass through the meter by way of the tube T, the valves and the measuring-cups entering the meter-body after being measured and leaving through the tube A², or can first enter the meter-body through the tube A² and discharge through the tube T after being measured. The latter, however, is probably to be generally preferred, as any sediment which might be in the fluid would in the first case be deposited mainly in the cups, while in the second case it would be deposited in the meter-body, whence it can be easily removed.

Having thus described my invention, I will now proceed to explain its operation. Suppose the meter to be properly set and connected with the supply and distributing pipes, and the fluid to be measured turned on. Suppose the fluid to enter through the tube T. It will find the valves in position so that it can pass by way of the valve recesses and ports and the corresponding tubes, S S', to the corresponding cups, M M', charging them with fluid, forcing them outward, while at the same time forcing the opposite cups, M M', into the liquid L and chamber II, discharging their contents through the corresponding tubes, S S', and valve-ports (now uncovered) into the meter-body, whence it escapes by the tube A². This motion of the cups M M M' M' causes the crank-shaft a to revolve, at the same time moving the valves and regulating the lead of the two sets of cups one on the other, and causing the cups to alternately charge through the valve-recesses, the covered ports, and the corresponding tubes, S S', and to discharge through the uncovered ports and corresponding tubes into the meter-body.

When the meter is connected in the opposite way, the fluid entering the meter-body by the tube A² finds one valve-port of each of the valves uncovered and passes through them and the corresponding tubes into the corresponding cups, M M', charging them and forcing them outward, while the opposite cups are forced into the liquid L and the measuring-chamber, discharging their contents through the corresponding tubes, the valve-recesses, and the tube T. Of course this motion sets the crank-shaft a, &c., in revolution, but in the opposite way to that in which it revolves when the fluid is passing through in the way first described.

In order to remove sediment or other deleterious substance from the meter, I provide a

receptacle, B², and plug C² in the lower part thereof. In Figs. 1, 2, and 3, D² is a channel formed around the edge of the lower half to catch any such deleterious substance which 5 might be condensed on the meter-case and convey it, by way of the channel E², to the aforesaid sediment-receptacle B².

What I claim is—

1. A duplex oscillating meter formed of the 10 cups M M' M', the measuring-chambers H H, for containing a sealing-fluid, inlet and outlet pipes, and suitable valves and valve-mechanism, substantially as described.
2. In a duplex oscillating meter, the combination, with the oscillating measuring-cups, 15 of the yokes, arms, pivoted link-connections, crank-shaft and cranks, and slide-valves and inlet and outlet pipes, substantially as described.
3. In a duplex oscillating meter, the combination of the measuring-chambers H H, the 20 sealing-fluid L, the tubes S and S', and inlet T, the slide-valves, the measuring-cups M M

M' M', the yokes N N N' N', the arms O O', the links k and l and e and h, and the crank-shaft and cranks, substantially as described. 25

4. The combination of the sliding valves, the crank-shaft a, chair b, crank-disks c c', the crank-pins f and g, and the links e and h, k and l, and arms O and O', having link-pins 30 m and m', all arranged substantially as set forth.

5. The combination of the measuring-cups and their yokes with the screws n² n², the lugs P P, and pillar Q, the screws or adjustable 35 bearings R R, and bearings r r, substantially as set forth.

6. The groove D² and channel E², in combination with the meter-case and the sediment-receptacle B², substantially as described. 40

In testimony whereof I have hereunto subscribed my name.

CHAUNCEY N. DUTTON.
